FLEXIBLE FOOT FOUNDATION

Maurice K. Anderson, Seattle, Wash.

Application November 14, 1940, Serial No. 365,697

19 Claims. (Cl. 36—71)

My present invention is an improvement on the inventions of my two patents No. 2,235,821, issued March 25, 1941, for a Sole conformer for shoes, and No. 2,288,665, issued July 7, 1942, for a Foot foundation.

As has been explained in those applications, while many arch supports have been proposed, no foundation device for the correct support of the sole of a wearer's foot has been available which could be fashioned to precisely the individual warped shape required by establishing the proper length of spacer means over the entire critical area. In my previous foot foundations disclosed in the above mentioned patents a multitude of individually adjustable supporting members or screws were provided, by regulation of which the conformation of a foot sole-contacting plate could be altered to suit the particular characteristics of the foot with which it was to be used. This same general principle has been employed in the devices disclosed herein also, but the general structure of the foot foundation has been improved.

In my first patent the adjustable spacer members were mounted in a rigid metal plate. I found that this construction was not objectionable where the area of the foot over which the plate extended was small and located principally beneath the foot arch. When such a rigid plate was extended forwardly beneath the ball of the foot and rearwardly beneath the heel, however, sufficient flexibility of the shoe and foot support was not afforded, and consequently in my second patent mentioned the rigid metal foundation plate was made of sections, preferably three, hingedly or otherwise flexibly interconnected, so that the foundation plate would bend at the most important locations, particularly just to the rear of the ball of the foot and between the heel and the foot arch. Even such a construction, however, I found to have disadvantages. In order to give a sufficient range of adjustability the metal plate into which the spacer or contour regulating members were screwed had to be quite thick. As a result the weight of the foot foundation as a whole was rather great. Further, instead of being able to flex progressively with the foot while still supporting the foot arch, this hinged form could flex only at specified locations, so that the foot was not properly, contiguously, and comfortably supported in all positions of the foot assumed during walking. It was also rather difficult to rebuild a shoe satisfactorily to receive the metal types of foot foundations.

My improved foot foundation herein disclosed

also employs a multitude of spacer or contour controlling members, but instead of these being mounted in a metal plate, they are received in metal sockets or collars inserted into a flexible base plate of leather or plastic material. This base plate may be the usual shoe insole, so that my improved foundation may be built into the shoe in its initial construction. Even after the shoe has been constructed a part of the original insole can be cut out and my improved foot foundation can be inserted directly in the cavity thus provided, to become an integral part of the shoe.

As a second type, my foot foundation can be made to be installed in a shoe by shoe repair shops without mutilating in any way the original construction of the shoe, and is especially well adapted for incorporation in a shoe having a relatively thin insole. In this case my device is formed as a supplemental insole, which either can completely cover the sole of the shoe or which is formed of two sections, the forward section in the toe portion of the shoe merely being a filler, and the portion from about the ball of the foot back to the heel constituting the base plate proper. Where this type covers the entire sole of the shoe it may be permanently secured in place, suitable provision being made to prevent lateral and lengthwise movement with respect to the shoe, or it may be made removable. Where only the rear part of such a supplemental insole forms the base plate of my foot foundation, such portion is preferably made removable, but is fitted to the permanently secured toe portion of the supplemental insole so that their upper surfaces at their abutting edges will be held in smooth continuity.

My improved foot foundation may take still a third form, namely, one in which it can be sold directly to the customer as an insertible inner sole. In such case no reconstruction or securing to the shoe whatever is necessary, the only fitting required being possibly to trim the edge of the base plate so that it will fit snugly within the shoe about its edges. Such trimming may be necessary so that a given size foot foundation may be fitted correctly to either a pointed toe or a rounded toe shoe, or so that only one, or a few sizes need be manufactured and stocked. After the desired adjustment of the foundation's contour is made the base plate may merely be slipped into the shoe, as any inner sole. Its base plate may be tapered toward the ends from the arch portion if desired, to occupy as little space as possible. When adjusted to meet the require-

ments of the individual wearer the foundation may be permanently glued in place, but obviously even this operation will not require the services of a shoe repair shop. It will probably be desirable, however, to have a foot specialist fit the foundation so that it will be adjusted to support the foot scientifically correctly, as well as comfortably.

As in the foot foundation disclosed in my Patent No. 2,288,665, I prefer to use individual headed spacer members, usually of the screw type. I have found, however, that fixed convex heads of oval shape, or tilttable heads are satisfactory. In addition the heads of the spacer members may be up or down, and adjustment of such members may be made by providing screw driver slots in the heads or in the ends screwed into the sleeves, whether or not the heads are tilttable. Instead of employing threaded shanks and sleeves the inserted ends may merely snap into place, in which case an assortment of spacer members of different lengths would be provided, from which the appropriate lengths for the various positions would be selected. Also while a large number of sockets for spacer members, distributed over a wide area, would be provided, such members would be inserted only at the locations necessary to obtain the desired contour.

If it should be found that when my flexible base plate is used the original shoe construction does not constitute a sufficiently rigid supporting structure, a metal plate may be inserted in the shoe sole to afford the desired stiffness. The type of upper sole contour plate employed may also be varied. In most cases it will probably be preferred to use a conformable, thin, metal sheet beneath a thin leather piece on which the foot rests. If the spacer member heads project downward from the foundation base plate, however, such a metal sheet may be unnecessary, and if the side of the foundation plate opposite the spacer members is sufficiently smooth, even the leather piece may not be required.

It will be understood that with my present foot foundation the sole contacting surface may be easily shaped to conform exactly with the foot, yet it will be sufficiently pliable to support the foot in all flexed positions assumed during walking. Such a device may be constructed in various ways to be installed by the shoe manufacturer, shoe repair shop, or wearer. It either may be initially, or subsequently may become, an integral part of the shoe; it may be removably secured in a finished shoe, or it may be merely slipped into a shoe as an accessory. In any case it will be very light, and while affording correct support for the foot in all flexed positions of the shoe, will not make it cumbersome or noticeably increase its weight.

Not only is the base plate of the foot foundation made flexible, but an additional shock absorbing effect may be obtained, if desired, by mounting the spacer members in sockets resiliently secured in the base plate. Additionally, or alternatively, the heads of the spacer members themselves may be provided with a thin resilient covering, such as of rubber. When the foot foundation is installed with the spacer heads projecting downwardly, such a rubber surface also tends to grip the inner side of the shoe sole to assist in preventing slippage between the inserted type of foot foundation, which is not positively anchored, and the shoe. If such shock absorbing qualities are not desired, but additional grip is wanted, the spacer member heads may be

knurled or roughened to dig into the shoe sole.

These various embodiments of my improved foot foundation and details of its construction are illustrated in the drawings, and while certain types of spacer members have been shown in particular modifications, it will be understood that a given type of spacer member is adapted for use in most or all of the various forms of foundation.

Figure 1 is a plan view of the built-in form of my foot foundation, showing the shoe upper and parts of the foundation broken away, while Figure 2 is a longitudinal section on line 2-2 of Figure 1.

Figure 3 is a plan view of a different form of built-in foot foundation, showing the upper portion of the shoe and parts of such foundation broken away, and Figure 4 is a partial longitudinal section of this form taken on line 4-4 of Figure 3.

Figure 5 is a plan view of the supplemental type of my foot foundation, showing the shoe upper and part of the foundation broken away, Figure 6 is a longitudinal section through this type taken along line 6-6 of Figure 5, and Figure 7 is a transverse section through the same form taken along line 7-7 of Figure 5.

Figure 8 is a partial plan view of a different form of the supplemental type of foot foundation, with the shoe upper and portions of the foundation broken away, and Figure 9 is a longitudinal section taken on line 9-9 of Figure 8.

Figure 10 is a partial plan view of still a different form of supplemental foot foundation, showing the shoe upper and parts of the foot foundation broken away, while Figure 11 is a partial longitudinal section taken on line 11-11 of Figure 10.

Figure 12 is a fragmentary plan view, having parts broken away, of a slightly modified form of supplemental foot foundation, but similar to that shown in Figure 10, and Figure 13 is a longitudinal section taken on line 13-13 of Figure 12.

Figure 14 is a plan view of an insertible type of foot foundation by itself, while Figure 15 is a longitudinal section taken along line 15-15 of Figure 14, showing such a foundation inserted in a shoe, parts of which have been broken away, and Figure 16 is a transverse section taken along line 16-16 of Figure 14.

Figure 17 is a fragmentary plan view of the same type of foot foundation employing a different type of spacer member, and Figure 18 is a longitudinal section taken on line 18-18 of Figure 17. Figure 19 is an enlarged section showing in detail one of the spacer elements incorporated in the foot foundation of Figures 17 and 18.

Figures 20, 21, 22, and 23 are fragmentary sectional views showing different types of spacer units and sockets which may be incorporated in any of various types of my foot foundation.

By a "built-in" type of foot foundation I refer herein to one incorporated in a shoe during its process of manufacture, or which is received flush in a recess made by cutting out a section of the original shoe insole. I refer to the type of foot foundation which is secured against lateral or lengthwise movement by means secured upon the shoe sole, but which does not require any cutting out of the original shoe inner sole, as the "supplemental" type of foot foundation. An "insertible" foot foundation is one which may merely be inserted in place in the shoe after proper adjustment without any of the original shoe sole being cut out, and which is not secured to such sole by any locking members installation of

which would require the services of a shoe repair or rebuild shop. In other words, this latter type can be sold directly to the customer for insertion in a shoe without any modification of the shoe construction, and may be inserted, perhaps after edge trimming, just as an ordinary loose inner sole is inserted.

The built-in type of foot foundation shown in Figures 1 and 2 would be incorporated in the shoe S at the factory. The usual insole of the shoe would be omitted, and would be replaced by the foot foundation base plate 1, which is flexible over its entire extent, being made of stiff leather similar to the usual shoe insole, but of somewhat greater thickness, or of equivalent material. From one surface of this base plate projects a number of spacer members or studs. To hold these, into the base plate may be inserted, prior to its incorporation in the shoe, a multitude of spacer member or stud sockets, suitably arranged over as large a portion of the base plate as desired. While the spacer members and sockets may take various forms, as will be described hereafter, one satisfactory form is the screw type 10, which is threaded into a socket or sleeve 11 having a flange at its receiving end. This socket is inserted in the base plate 1, preferably extending completely through it to afford maximum range of adjustment, and with the sleeve flange recessed or countersunk into the base plate, as shown in Figure 2. The head of each screw stud in this type of foot foundation would project upward, as shown, because the base plate 1, as previously stated, serves as the shoe insole, and would be permanently secured to the normal outer sole. The stud heads are preferably of slightly convex or oval shape, as distinguished from hemispherical shape generally designated round heads. Overlying the screw heads to form the foot supporting surface is a thin conformable plate 12, which may be of metal of a sufficient thickness to support the wearer's weight without local deformation, yet which will conform, preferably deformably, to the warped surface defined by the upper ends of the screws 10.

In order to finish the inner side of the foot foundation a covering piece of soft leather 13 may be provided, which will extend over the entire area of the sole, although the metal plate 12 need extend only over that portion in which the spacer or contour controlling members are located. The metal sheet 12 and leather cover 13 are preferably secured together, such as by spaced rivets 14, and this composite cover may be secured to the base plate 1 by a forward screw 15 and a rear screw 16. The screw 15 may be tightly screwed into place to clamp the metal plate 12, as shown in Figure 2, its head being countersunk into the leather piece 13. The screw 16, on the other hand, will not be screwed down tightly, so that a sliding action will be afforded between its shank and a slot 17 formed in the metal plate 12. As the shoe sole and foundation base plate flex during walking, the metal and leather cover, thus slidably connected at the rear, may slip to a slight extent over the base plate of the foundation. The leather cover piece 13 is cut out to accommodate such sliding of the screw head, as shown.

A typical arrangement of screws 10 in sockets 11 is shown in Figure 1, where it is desired primarily to support the arch. The screws illustrated have fixed, slightly rounded heads provided with cross grooves to receive a screw driver for adjusting the individual screws up or down.

Screws having tilting heads, as shown in Figures 3 and 4 for example, may be used instead. When it is desired to establish or alter the conformation of the foot supporting surface as defined by these screw heads, screws 15 and 16 are removed, and then the cover unit, composed of the plate 12 and leather cover piece 13, may be slipped out of the shoe while the screws are adjusted individually. The cover unit is then put back into place, and the shoe is tried on. This procedure is repeated until the desired warped contour is established, and then the screws 15 and 16 are replaced to secure the composite cover in place. It will be noted that screw sockets are provided from the back of the heel to a point slightly forward of the ball of the foot, so that the proper sole-conforming shape may be established over this entire area by inserting screws where necessary and relatively adjusting them to the proper height.

As previously pointed out, the screw sleeves or sockets 11 have flanges on their upper ends so that the weight of the wearer will be distributed through them to the base plate 1, instead of the force tending to push the sleeve out of the base plate, as would be the case if an unflanged sleeve were used. On the other hand, the purpose of screws 15 and 16 is to hold the cover unit down at its ends, instead of supporting it, and consequently the sockets for these screws are inverted, so that the flanges lie beneath the base plate 1, as shown in Figure 2.

When the arch portion of the wearer's foot supports its proper weight on the raised portion of the foot foundation it may be that, at least when a wearer first begins to use it, an unusually great weight is carried by the shoe arch. Consequently it may be necessary to strengthen this portion of the shoe by recessing into the upper surface of the outer sole, during manufacture of the shoe, a metal plate 18. The extent of this plate forward and rearward is, of course, a matter of choice, but it should not extend ordinarily forward of the ball of the foot or appreciably behind the front of the heel, since these are the regions of principal flexure. In most cases this plate need not make the shoe absolutely rigid, but it is intended to act as a strengthening and stiffening element. It may be of more or less flexible material according to the amount of stiffness desired and the rigidity and ruggedness of the rest of the shoe. Such an insert, however, eliminates the necessity of an unusually heavy sole being required for effective use of my foot foundation of the built-in type.

The type of foot foundation shown in Figures 3 and 4 is similar to that just described, except that instead of the spacer member sockets being inserted in the shoe insole before it is incorporated in the shoe, a portion of the regular insole 2 is cut out, leaving a marginal portion 20 at the rear of the shoe, and the entire toe portion 21 of the insole in place. This cut-out portion, as shown in Figure 4, is the full thickness of the insole, but sufficient width is left about its margins so that the securing of the shoe upper to the sole will not be disturbed. The piece of leather 2 thus cut out, or one of similar size and shape, is apertured for reception of spacer member sockets 22, which may be the same as the sockets 11 shown in Figure 1. Again the area over which these sockets are distributed is largely a matter of choice, and spacing screws 23 are inserted in only those sockets required to afford the proper shape of sole supporting surface in each individual case. If it is known before a

portion of the regular insole is removed just what distribution of spacer members will be required in a particular instance, it may not be necessary to cut out as large a portion of the insole as indicated in Figure 3. The socket-carrying insert may be removably fitted in place, or it may be secured permanently in this type of construction.

The screws 23, as shown, are different from the screws 10 in that their heads are tiltable with respect to their shanks, as indicated in Figure 4. A slightly upset stem of reduced diameter extending through a central aperture in each head prevents disconnection of the head from the shank, but provides a rounded shoulder upon which the heads rest and can tilt. The tops of such stems, however, are slightly countersunk below the heads in every tilted position, so that the pressure of the foot is carried by the tilting heads. These contact the cover plate contiguously over their whole area, instead of over a portion only as do fixed head screws such as shown in Figure 2. Moreover, in expanding the screw shank to hold the head in place a deep cross groove can be formed, which not only will serve to flare the end of the stem, but will provide a socket into which a rotating tool may be inserted for adjusting the screws. Such a socket may be similar to that of the "Phillips" screw, for example, or it may be of any shape which will afford sufficient turning grip within a small area. While this type of screw is illustrated as being used in this embodiment of my invention, it will be understood that the same type as shown in Figures 1 and 2 may be used instead, or this type may be used in the form of foundation shown in Figures 1 and 2. In either case the fit of the threads is quite snug, so that after the screw has been turned to the proper position it will not be rotated involuntarily during use.

While with the tilting head type of screw it is not as necessary to use a conformable thin metal cover plate, such a plate, indicated at 24, would ordinarily be used. This plate may be imperforate or, as indicated, it may contain a large number of small, closely spaced holes, which will tend to lighten it somewhat, and also provide ventilation. A similarly perforated plate could be used in the form of my foundation shown in Figures 1 and 2, if desired. This plate, as before, is covered with a thin flexible piece of leather 25 for finishing purposes. The leather sheet and metal plate are also likewise held together by rivets 26, but in this case, instead of the cover unit being removed from the shoe for adjustment purposes, the holding screw is replaced by a hinge. The rivets 26 extend through the upper leaf of hinge 27, while its lower leaf is anchored to the inserted base plate 2, so that the cover may merely be tipped up about its front end as an axis for access to the screws 23. The broken line position of Figure 4 illustrates the cover in a tilted position.

The supplemental type of foundation shown in Figure 5 covers the entire area of the sole, as does the form of built-in foundation shown in Figure 1, except for small locking pieces which are fixed to the sole structure of the sole. This type of my device is more appropriate where an unusually thin insole is used in the shoe construction. Such locking pieces may include two upward projections 30, mounted on the insole one at each side of its heel portion, which fit complementary notches provided in the superposed base plate 3 of the foundation. At the forward portion of

the shoe are additional locking projections 31 secured to the shoe insole, which likewise engage notches of complementary shape provided in the forward portion of the base plate 3. Such projections will normally be of the same height as the thickness of the base plate. By this means the base plate may be securely anchored in the shoe against forward, rearward, or lateral displacement while still being removable for adjustment.

The spacer member sockets 32 are of the same type previously described except that the illustration shows a greater number spread over a larger area than even in the form of Figure 1. In particular it will be noted, in Figure 7, that screws 33 are in place even slightly forward of the ball of the foot, to support the transverse forward arch, while as shown in Figure 6 a slight cup is provided into which the heel of the foot seats. It will be seen, therefore, that extremely wide variations in the contour of the foot supporting surface may be made to suit the requirements of the individual wearer.

As before, a pliant, conformable metal plate 34 overlies the screw heads, and is secured by rivets 35 to a leather finishing sheet 36. This cover unit is secured to the base plate 3 by countersunk screws 37 and 38, respectively. The screw 38 is sufficiently loose that the portion of plate 34 engaged by it may slide with respect to the base plate 3 to some extent, as described in connection with the form shown in Figure 1.

Figures 8 and 9 illustrate generally the same type of supplemental foot foundation as in Figures 5, 6, and 7, except that the sleeves 32 are disposed in an area which does not extend quite as far forward. With the coverage shown in Figure 5 it is necessary to use locking pieces at the edges of the base plate 3 to hold it in place, but if a less extensive distribution of spacer member sockets, such as shown in Figure 8, is considered to be sufficient, a central rib 39 may be secured upon the sole of the shoe for projection into a complementally shaped aperture in base plate 3. When this type of interlock is employed the rear abutments 30 are unnecessary, since the locking piece 39 not only resists forward, backward, and sidewise bodily movement, but also prevents rotation of the base plate with respect to the shoe. This single locking member, therefore, will replace the two members 30 as well as the two members 31 shown in Figures 5, 6, and 7.

If in the supplemental type the area over which the spacer members are to be distributed need not be even as large as shown in Figures 8 and 9, a toe piece equal in thickness to that of the base plate 4 may be permanently secured in the shoe, as indicated at 40 in Figures 10 to 13, inclusive. The rear edge of the fixed toe piece and the forward end of the base plate 4 are shaped complementally so that they will engage each other contiguously. Moreover, the fit of the abutting ends prevents lateral relative movement of the two parts, and the front end of the base plate is recessed under, and thus is held down by, the rear edge of the toe piece. The shape of this joint in plan, shown in Figures 10 and 11, is generally wedge-shaped, which assists in holding the base plate from turning. To keep the front end of the base plate from rising, the rear edge of the fixed toe piece is under beveled while the front edge of the base plate is formed with a complemental standing bevel, which interfit to form the joint 41. Rearward movement of the base

plate is prevented by contact of its rearward end with the heel of the shoe. If a positive anchoring engagement is desired, cleats or projections such as 30 in the form of Figure 5 may also be provided in the devices of Figures 10 to 13.

In all the forms thus far described the spacer members have projected upward from the base plate, such plate resting in contiguous engagement with the shoe sole. Such base plate, being of leather, plastic composition or similar flexible material, bends with the shoe and foot during walking, but such bending is no more than that required of the shoe sole itself. In the form of my foot foundation shown in Figures 10 and 11, the heads of the screws 44 project downward, instead of upward as previously described. With the screws thus projecting downward the base plate 41 instead of conforming to the shape of the shoe sole will itself assume the conformation of the foot sole, as determined by the individual adjustment of the spacer screws. While the base plate must still be thick enough to receive screw shanks of considerable length in order to provide sufficient adjustment, the leather or plastic material of which it is made must be quite flexible or deformable in order to be shaped locally to the foot and to be supported by all the spacer members. A sheet metal contour plate is therefore not nearly as necessary as where the screws project upward as in the forms previously described.

Naturally the flanges of the sockets 43 in this type will be beneath the base plate to resist the upward thrust of the screws, instead of being countersunk into its upper surface. While screws of the same general type as shown in Figures 5 and 6 may be employed, a single cross groove only in the screw head may be used. The base plate 4 would, of course, be removable from the shoe so that adjustment of the amount of screw projection could be made by a screw driver or other suitable tool inserted in such grooves. When the screw heads project downward an additional engagement tending to prevent rearward movement of the base plate 4 away from the fixed piece 40 is provided, for the heads will exert considerable frictional resistance to such movement by their engagement with the insole of the shoe. Moreover such frictional force may be increased by employing a screw such as shown in Figure 22 having a composite head, the lower portion 5 of which is of rubber or equivalent friction material. Another way in which the friction may be increased is by knurling or otherwise roughening the surface of the head, as at 50 in Figure 23, so that the points thus formed will embed themselves in the shoe insole. The grip of the screw heads thus afforded also prevents involuntary rotation of the screws which would alter the desired warped contour of the base plate corresponding to the originally adjusted positions of the screws.

As before, a composite covering unit may be provided, including a thin metal sheet over which is placed a piece of soft leather, but, as stated, is not necessary, and even the soft leather piece 42 may be eliminated without undue discomfort. If this leather sheet covers the entire area of the base plate 4 and toe piece 40, as is preferred, no fastening need be provided for it. Particularly can the metal sheet, and perhaps even the cover piece of leather, be omitted, if the screw sockets, instead of having through apertures, are of the type shown at 43, in which the upper end of each is closed by a wall which lies flush with the surrounding portion of the base plate surface. With this construction the screws 44 may have slightly shorter shanks, or, if they are of the same length 75

as used with sockets which extend completely through the base plate, a somewhat thicker base plate will be required, and the sockets will be correspondingly longer, in order to afford as great a range of adjustment.

In Figures 12 and 13 the front end of the base plate 4 and the fixed toe piece 40 are interconnected by a rabbet joint 45, tapering in width from the center of the shoe toward each side, 10 the overlapping part of the rabbet being provided on the toe section 40 and the front end of the base plate having an underlapping feather. As in the form of Figures 10 and 11 described above, rearward movement of the base plate is here prevented by engagement of its rearward end with the heel of the shoe and by the frictional engagement of the screw heads with the shoe insole. Lateral movement of the front end of the base plate is prevented by the curved formation of the rabbet joint 45, and its taper in plan tends to prevent swinging of the base plate, for such pivotal movement would necessitate also its lengthwise shifting. Arcuate movement of the joint 45 would shift a wide portion of the base plate feather into engagement with a narrow portion of the toe piece recess, so that the upper edges of the joint instead of being in abutment would be pushed apart, necessitating such bodily longitudinal movement of the base plate 4, which is prevented by contact with the shoe, as stated. Angular, as well as lateral, shifting is thus prevented.

While in this form also the screw heads are shown projecting downward, the bores of sockets 46 extend clear through the base plate 4. The heads of screws 47, as shown in Figure 13, are universally tiltable, as are the heads of the screws 23 shown in Figures 4 and 5. In this case, however, in order to enable adjustment of the amount of screw projection from above without removal of the base plate 4 from the shoe, the inserted ends of the screw shanks are slotted to receive a screw driver, as shown in Figure 12. As in the case where screws having fixed heads are used, 45 the tiltable heads of these screws may be covered with rubber in the manner shown in Figure 22, or may be knurled, as in Figure 23, in order to improve the grip of such heads upon the shoe insole. Because, when this type of socket is 50 employed, the upper surface of the base plate would be perforated, I prefer to provide a sheet of thin deformable metal 48 beneath the leather cover piece 42, as has been described in previous modifications. This metal sheet should be held 55 in place by a screw 49, countersunk in the leather sheet 42.

The last major type of foot foundation embodying my invention, and which I have designated as the "insertible" type, is shown in Figures 14 to 18, one modification being illustrated in Figures 14, 15 and 16, and another in Figures 17 and 18. When this type of foot foundation is employed no part of the original shoe construction need be cut out, and no holding members need be attached to the shoe sole. All that is necessary is that the base plate 6 be trimmed in contour so that it will fit snugly within the shoe S, as shown in Figure 15, the ends and side edges preferably being beveled to engage contiguously the shoe upper in the manner indicated. The projection of the individual screws 60 from their sockets 61 may then be adjusted as previously described to provide the proper shape for the foundation.

This particular form is best adapted for use

in less severe cases of foot ailment, where no special shoe construction is necessary, and the contour can ordinarily be reasonably well established by the user himself, although greater benefits can usually be obtained if fitted by an expert. The screw sockets 61 may be provided only over the arch portion of the foot foundation, as in Figures 17 and 18, but preferably are also located around the margin of the heel as shown in Figure 14. Screws would be inserted only in those sockets where an alteration in effective thickness of the foundation is required, as described in connection with the previous types, to shape the upper surface of the foundation to the desired foot conformation.

To make this type of foundation better adapted for insertion in a shoe, so that the least possible increase in sole thickness is produced, the heel and toe sections of the base plate, designated 62 and 63, respectively, may be tapered from the central arch portion to a lesser thickness. The front end of the base plate, for example, may be either of thinner, uniform thickness as shown in Figure 15, may be tapered progressively as in Figure 18, or may even feather out short of the toe of the shoe. The greater thickness is required in the central portion to receive the sockets 61, which may be of closed end type and be fitted with downwardly projecting screws such as previously described in connection with Figures 10 and 11. As mentioned in such description, where, as shown in Figure 15, the spacer members project downward, even a leather cover piece need not be used because the closed socket ends lie flush with the upper surface of the base plate, as shown. Again the base plate, while thick, since it acts as the foot sole conforming member, must be made of leather or equivalent material which is quite pliable. Additional local flexibility may be afforded, as in the center of the heel portion 62, for example, as shown in Figures 14 and 15, by splitting the base plate part way through from the bottom to allow greater expansion of its under surface, and hence greater cupping of its upper surface to receive the heel, when the margin is raised by the encircling spacer members.

It will be evident that this is the simplest type of foot foundation, composed of only the base plate, inserted sockets, having closed ends, spacer members, such as screws, fitted into such sockets as may be necessary, and perhaps a thin leather covering sheet. No modification of the original shoe construction is required, and the foundation may either be used in the same manner as an insertible inner sole or, after the spacer members are properly adjusted, it may be permanently glued in place, as may an inner sole, to form thereafter an integral part of the shoe.

The spacer members of Figures 17 and 18, instead of being of the screw type, have their inserted shank ends and their cooperating sockets 64 and 65, respectively, formed as glove fastener snaps. Their construction is shown on an enlarged scale in Figure 19. The heads 66 of these spacer members are preferably of the tilt type, as are the heads of the screws shown in Figures 3 and 4, but, if desired, the heads of such snap members may be of the oval, fixed type.

Where these snap spacer members are employed their effective lengths cannot be adjusted as can that of the screws, but they will be available in a variety of lengths, as shown in Figure 18, so that those of appropriate lengths may be selected and snapped into sockets at the loca-

tions required to form the proper sole-conforming contour. The heads of such spacer members may be disposed downward, as are the screw heads of Figure 15, in which case no cover would be required. If the heads project upward, however, a cover unit including a thin flexible metal plate 67, over which is placed a soft leather sheet 68, similar to those previously described, would be provided. This may be secured in place by rear and front countersunk snaps 69, which snap into appropriate shallow sockets 65 located in the thinner portions of the base plate 62 and 63, respectively.

The rubber face 5 on the screw head illustrated in Figure 22 not only provides a better grip upon the inner sole, as explained, but also affords a certain shock absorbing action for cushioning the foot during walking. A similar shock absorbing action may be obtained by the use of a rubber sleeve 70 encircling the screw socket 7, as shown in Figure 21. Such sockets may be like any of those previously described, having either a closed end or a through bore, and may be for reception of a screw or a snap head type spacer member. With this construction the aperture in the base plate 71, in which the socket is mounted, is not countersunk, but is of constant diameter throughout its depth, which diameter is at least as great as the diameter of the socket flange. The rubber sleeve may either resiliently grip the socket shank or be bonded to it, and its periphery will be glued or otherwise secured to the base plate 71. As pressure is applied to the head of the spacer member received in socket 7, therefore, the resilient collar 70 will be compressed somewhat by the socket flange, thus allowing the screw head to yield somewhat with relation to the base plate, resulting in the cushioning action.

Because it will be desirable ordinarily not to have spacer members in all the base plate sockets, where the spacer members project downward it is desirable to cover the lower surface of the base plate with cloth 8, such as felt, as shown in Figure 20. This may be of a thickness equal to that of the socket flanges so that they need not be countersunk into the base plate proper. Where the spacer members project upward, the entire under surface of the base plate 50 may be cloth covered. The purpose of such covering is to prevent squeaking which otherwise might result from the rubbing of the lower surface of the base plate on the upper surface of the shoe sole if both are of leather. If all relative movement between such two surfaces is prevented, or the materials used will not squeak, such covering need not be used.

What I claim as my invention is:

1. A foot foundation for a shoe, comprising a base plate at least the entire metatarsal area of which is composed of inherently flexible material, and a plurality of unyielding spacer studs projecting from said base plate in sufficient number and sufficiently closely spaced to define cooperatively and with said base plate a substantially incompressible foundation of varying thickness in different portions for engagement of one side thereof with the upper surface of the shoe sole, the other side thereof defining a warped surface conforming to the shape of a wearer's sole.
2. A foot foundation for a shoe, comprising a base plate at least the entire metatarsal area of which is composed of inherently flexible material, a cover sheet of flexible material and of uniform thickness, unyielding means interposed between

said base plate and said cover sheet of non-uniform effective height, for varying the thickness of different portions of the substantially incompressible composite foundation defined by said base plate and said cover sheet.

3. A foot foundation for a shoe, comprising a base plate at least the entire metatarsal area of which is composed of inherently flexible material, a multitude of spacer stud sockets inserted in distributed arrangement into said base plate, and spacer studs received in said sockets, individual spacer studs projecting from their sockets different distances beyond the surface of said base plate, for increasing locally the effective thickness of various portions of said foundation.

4. A foot foundation for a shoe, comprising a leather base plate, a multitude of spacer member sockets inserted into said base plate in distributed arrangement over a substantial area, each socket being flanged and countersunk in said base plate and being of a length substantially equal to the thickness of the base plate at the location of insertion, spacer members received in said socket members and projecting various distances from one surface of said base plate, a thin conformable metal sheet overlying said spacer members and conforming to the warped surface defined by the projecting ends thereof, means securing said metal sheet to said base plate, and a thin leather sheet overlying said metal sheet and secured thereto.

5. A foot foundation for a shoe, comprising a base plate having therein a plurality of spacer stud sockets distributed over it and opening downwardly, and a plurality of individual spacer studs seated in said sockets, and projecting different distances downwardly below the lower surface of said base plate for engagement with the upper side of the shoe sole, said base plate being sufficiently flexible to conform to the contour of the wearer's sole as determined by the different relative projections of the individual spacer studs below said base plate.

6. A foot foundation for a shoe, comprising a flexible base plate, a plurality of spacer stud sockets having one end closed, inserted in spaced locations through said base plate with their closed ends substantially flush with the upper surface of said base plate to make such surface continuous, and a plurality of spacer studs received in the open ends of said sockets, and projecting downwardly below the lower surface of said base plate for engagement with the upper side of a shoe sole, to define a foot foundation varying in effective thickness for shaping the upper surface of such base plate to the contour of the wearer's sole.

7. A foot foundation for a shoe, comprising a highly flexible base plate, a plurality of spacer stud sockets having one end closed and the other end flanged, inserted in spaced locations through said base plate with their closed ends upward and substantially flush with the upper surface of said base plate to make such surface continuous and with their flanged ends downward and bearing against the base plate, and a plurality of spacer studs received in the open ends of said sockets, and projecting downwardly below the lower surface of said base plate for engagement with the upper side of a shoe sole, to define a foot foundation varying in effective thickness for shaping the upper surface of said base plate to the contour of the wearer's sole.

8. A foot foundation for a shoe, comprising a base plate at least the entire metatarsal area of

which is composed of inherently flexible material, a plurality of sockets inserted in said base plate and distributed over its area substantially from the rear of the heel portion to the metatarsal portion thereof, and separate spacer studs each received in one of said sockets, projecting various distances therefrom, and uninterconnected other than through said sockets and base plate, to define a warped surface conforming to

10 the sole of a wearer's foot.

9. The foot foundation of claim 8, and projections secured to the shoe insole and shaped for engagement with complementary recesses in the base plate to restrain the latter from bodily movement relative to the shoe insole.

10. A foot foundation for a shoe, comprising a base plate of flexible material overlying the heel and arch portions of the shoe insole, a fixed member overlying the toe portion of the shoe 20 insole, the back end of such toe member and the front end of said base plate being formed complementally for insertion of the front end of said base plate beneath the back end of said toe member, thereby to hold down the front end of 25 said base plate, a plurality of sockets inserted in said base plate, and spacer members received in said sockets and projecting therefrom different distances thereby to shape the foot foundation to the sole of a wearer's foot.

30 11. A foot foundation for a shoe, comprising a flexible base plate, a plurality of sockets inserted in said base plate about the margin of the heel portion thereof, the central part of said heel portion being free from sockets, and spacer members 35 inserted in said sockets for projection therefrom different distances to cup the heel portion of the foot foundation different degrees to correspond to the shape of a wearer's heel.

12. A foot foundation comprising a base plate, 40 a plurality of sockets arranged about the margin of the heel portion of said base plate and opening downwardly, and spacer members received in said sockets for raising the margin of the heel portion of said base plate, the central 45 part of said heel portion being free from sockets and being slit on its lower surface to increase the flexibility downward, for depression of the central part of the heel portion as the margin is raised by said spacer members.

50 13. A foot foundation for a shoe, comprising a base plate at least the entire metatarsal area of which is composed of inherently flexible material and having a plurality of sockets therein, and a plurality of separate spacer studs of different effective lengths, each having engagement with only one of said sockets, projecting from the surface of said base plate to increase the effective thickness of the foundation in varying degrees, and uninterconnected other than through said 55 sockets and base plate, said base plate being adapted to flex with the shoe in walking.

14. In a foot foundation, a base plate, an annulus of resilient material inserted in an aperture in said base plate, and a spacer member socket 60 mounted in said annulus in yielding relationship to said base plate.

15. A foot foundation for a shoe, comprising a base plate at least the entire metatarsal area of which is composed of inherently flexible material, and a plurality of separate spacer members individually adjustable in effective length projecting from the surface of said base plate in sufficient number and sufficiently closely spaced to define cooperatively and with said base plate 70 a foundation of variable thickness in different

portions for engagement of one side thereof with the upper surface of the shoe sole, the other side thereof defining a warped surface conforming to the shape of a wearer's sole, said base plate being adapted to flex with the shoe in walking.

16. A foot foundation for a shoe comprising a base plate at least the entire metatarsal area of which is composed of inherently flexible material, and a plurality of spacer screws threaded into said base plate in sufficient number and sufficiently closely spaced to define cooperatively and with said base plate a substantially incompressible foundation for engagement of one side thereof with the upper surface of the shoe sole, said screws being individually adjustable to change the spacing of their several projecting ends from said base plate independently for varying the thickness of different portions of said foundation, and for altering the warped contour of the side of the foot foundation opposite that engaged with the shoe sole to conform to the shape of a wearer's sole, said base plate being adapted to flex with the shoe in walking.

17. A foot foundation for a shoe, comprising a base plate at least the entire metatarsal area of which is composed of inherently flexible material, and a plurality of rigid spacer studs projecting downward from the under surface of said base plate, and forming feet therefor engageable with

the upper side of the shoe sole, for raising those portions of said base plate from which the spacer studs project to warp its upper surface conformable to a wearer's sole.

5 18. A foot foundation for a shoe, comprising a base plate at least the entire metatarsal area of which is composed of inherently flexible material, and a plurality of spaced studs each having its upper end inserted into said base plate and its 10 lower end resting upon the upper side of the shoe sole, and forming feet for raising the portions of the base plate into which the upper ends of said spacer studs are inserted to warp its upper surface conformable to a wearer's sole.

15 19. A foot foundation for a shoe, comprising a base plate at least the entire metatarsal area of which is composed of inherently flexible material, a multiplicity of rigid spacer studs of different effective lengths, each having its upper end inserted into said base plate and its lower end resting upon the upper side of the shoe sole, and forming feet of different lengths for raising in varying degrees the portions of said base plate 20 into which the upper ends of the spacer studs are inserted, to warp the upper surface of said base plate conformable to a wearer's sole, said base plate being adapted to flex with the shoe in walking.

MAURICE K. ANDERSON.
